[57] CLAIM

The ornamental design for a circular shelf and storage unit, as shown and described.

DESCRIPTION

FIG. 1 is a top plan view of a circular shelf and storage unit, showing my new design;

FIG. 2 is a front elevational view thereof;

FIG. 3 is a bottom plan view thereof;

FIG. 4 is a rear elevational view thereof;

FIG. 5 is a left side elevational view thereof;

FIG. 6 is a right side elevational view thereof;

FIG. 7 is a cross-sectional view taken substantially along line 7—7 of FIG. 1, and showing the inner rear side thereof in elevation;

FIG. 8 is a cross-sectional view taken substantially along line 8—8 of FIG. 1, and showing the inner front side thereof in elevation;

FIGS. 9A and 9B, joined side-by-side as shown in the diagram on FIG. 9A, comprise an enlarged scale perspective view of the front, top and inner rear side thereof; and,

FIGS. 10A and 10B, joined side-by-side as shown in the diagram on FIG. 10A, comprise an enlarged scale perspective view of the rear, top and inner front side thereof.
